ATTORNEY.

UNITED STATES PATENT OFFICE.

GEORGE W. GOETZ, OF MILWAUKEE, WISCONSIN.

CALCINING OR ANALOGOUS FURNACE.

SPECIFICATION forming part of Letters Patent No. 443,438, dated December 23, 1890.

Application filed June 4, 1890. Serial No. 354,198. (No model.)

To all whom it may concern:

Be it known that I, GEORGE W. GOETZ, of Milwaukee, in the county of Milwaukee, and in the State of Wisconsin, have invented certain new and useful Improvements in Calcining or Analogous Furnaces; and I do hereby declare that the following is a full, clear, and exact description thereof.

My invention relates to calcining and analogous furnaces; and it consists in certain peculiarities of construction, as will be fully set forth hereinafter and subsequently claimed.

In the drawings, Figure 1 is a vertical longitudinal section of one form of my improved device. Figs. 2 and 4 are like views of other forms, and Fig. 3 is a horizontal section on the line 3 3 of Fig. 2.

Heretofore in calcining furnaces a serious objection has often existed from the mixture of the ashes of the fuel employed with the material undergoing calcination. Another objection has been found in the inconvenience of interrupting the process of calcination to remove, for use or storage, portions already calcined, and a third objection has arisen from the necessity of a separate and frequently more or less remote place of storage for the completed product, and to remedy these objections, as well as to improve and simplify the general construction of such furnaces, are the principal objects of my present invention.

A, Fig. 1, represents the calcining-chamber of a furnace, which in this instance is of the style known as a "recuperator," having, however, a storage chamber or magazine B beneath the point constituting the hearth of a calcining-furnace of ordinary construction. C is the gas or oil pipe, and below this are the air-inlets D into the calcining-chamber, and connecting, as shown, by dotted lines, with the air-flues E E E of the recuperator and the outside air-flues F F F. G represents the smoke-outlets from the chamber A, communicating with the smoke-flues H H of the recuperator, and thence with the chimney-flue I. J J are a series of openings in the wall of the storage-magazine B, extending partly around the same and communicating with a bustle-pipe K, having a flue L leading to the chimney-flue I, said flue L having a conven-

iently disposed regulating-damper M, as shown.

In Figs. 2 and 3 I show my invention applied to a Siemens regenerator-furnace, A representing the calcining-chamber and B the storage-magazine, as before, C C' the gas or oil pipes, and D' G' the interchangeable or alternating air-inlets and smoke-outlets of the chamber A, as the case may be, E' E' representing the regenerative-chambers filled with the usual checker-work, and F' H' the interchangeable or alternating chimney-flue and outside air-flue, the location of the reversing-valve I' (shown in dotted lines in Fig. 3) determining whether F' or H' is the chimney-flue or air-supply flue, and therefore whether D' or G' are the air-inlets or smoke-outlets of the chamber A at any time. In the arrangement shown in said figures gas or oil from pipe C and air from flues D' is fired, and smoke escapes through flues G', and hence F' would be the chimney-flue and H' the air-supply flue in this instance. J J represent openings into the bustle-pipe K, as before, and the flue L from the pipe K must of course lead to a point on the chimney-flue beyond the valve I', as shown in Fig. 3.

In Fig. 4 I show my invention applied to a coal-fired furnace. A is the calcining-chamber, and B the storage-magazine, as before, having smoke-openings J J leading to a bustle-pipe K, with flue L leading to a chimney-flue. N represents a fire-bed or grating, and O a cupola. P P are doors leading into the calcining-chamber A in all the views, while Q Q are other doors at the base of the storage-magazine in all the views.

The furnace shown in Fig. 4 is fed with the raw material to be calcined or treated through the charging-doors R in the cupola O; but in the other forms illustrated I make use, preferably, of hoppers or chutes S, (having suitable cut-offs T,) leading to just above openings U in the tops of the chambers A, which openings are closed by suitable doors or slides V.

The operation of my devices will be readily understood from the foregoing description of their construction, taken in connection with the accompanying drawings.

I will first describe the operation of the furnace shown in Fig. 1. The raw material (such

as limestone) is fed through the hopper S and opening U into the chamber A, filling first the storage-magazine B, and then being spread evenly above the base or hearth proper of the chamber A, access thereto being had by means of the doors P. Gas or oil is then turned on in the pipe C, and uniting with air from the inlets D is fired and the process of calcination commences, being aided by the suction 5 through the openings J J, which serves to draw down the hot products of combustion from the hearth through the interstices between the masses or pieces of the material being treated, the smoke therefrom passing 10 through the bustle-pipe K and flue L to the chimney-flue I and thence out. The smoke and hot gases that escape through the outlets G pass through the recuperator-flues H in the usual manner, and thereby heat the air in the flues E E, as is well understood. The furnace shown in Figs. 2 and 3 is similarly fed and fired, and the passage of the air and the hot gases and smoke is that usual to furnaces of this general type.

25 The furnace shown in Fig. 4 is fed with the raw material through the doors R of the cupola O, as already stated, and access being had to the interior of the chamber A through its doors P. The said material is first raked 30 into the storage-magazine B until that is full and then spread over the surface of the hearth proper and the feeding continued until said material has filled the cupola O to nearly the charging point or about on a level with the 35 charging-floor W in said Fig. 4. As the material in the upper part of the magazine B and on the hearth becomes calcined, the raw material below is gradually withdrawn

through the doors Q until said magazine B contains only the calcined material, and then 40 this material is withdrawn as needed for shipment or to make room for the fresh material being constantly calcined above it, and hence (after the furnace has been started) the magazine B acts as a storage-chamber (in all the 45 forms shown) and with the material therein contained constitutes always a portion of the hearth of the furnace.

A very important use of my present invention lies in its adaptability for over-burning 50 limestone, magnesite, cement, or other substances, as this can be admirably done in my furnaces without the least mingling of the ashes of the fuel with the material being burned.

Having thus described my invention, what I claim as new, and desire to secure by Letters Patent, is—

In a furnace, the combination of a calcining-chamber, air and smoke passages communicating therewith, means for heating said chamber, a storage-magazine located beneath and forming a part of the hearth of said chamber, and a bustle-pipe having openings into said storage-magazine, and a damper-controlled flue leading to the chimney-flue of the furnace, substantially as set forth.

In testimony that I claim the foregoing I have hereunto set my hand, at Milwaukee, in the county of Milwaukee and State of Wisconsin, in the presence of two witnesses.

GEORGE W. GOETZ.
